INTERNAL COMBUSTION ENGINE

Filed Sept. 28, 1926

Inventor:
Robert Tardine
By Gillson, Mammoth
City.

UNITED STATES PATENT OFFICE

ROBERT JARDINE, OF DETROIT, MICHIGAN, ASSIGNOR TO RICH TOOL COMPANY, A CORPORATION OF MAINE

INTERNAL-COMBUSTION ENGINE

Application filed September 28, 1926. Serial No. 138,176.

In the conventional internal combustion engine as now commonly constructed, the guide for the poppet valve extends from a relatively short straight cool wall of the cylinder jacket through a relatively long curved hot wall of the exhaust port and projects into the port a substantial distance toward the valve seat. The valves are seated and ground in when the engine is cool. When it is warmed up the curved wall of the port, through which the valve guide projects, expands, and because its ends are rigidly fixed it bends, taking the valve guide with it, while the base of the guide is held rigid by the relatively cool flat wall of the jacket. On account of the comparatively great distance from the point where the guide passes through the wall of the port to the valve seat, a movement of a few thousandths of an inch at the juncture of the valve guide with the wall of the port produces a relatively great movement of the valve head with respect to the center of the seat, thus displacing the valve and preventing proper seating.

A portion of each exhaust valve stem in the conventional engine structure is directly exposed to the action of the exhaust gases, and a considerable length adjacent to the exposed portion is protected only by a valve guide which itself is directly exposed to the exhaust gases. This permits the valves to be unduly heated to expand very considerably, and therefore to require excessive clearance with the tappet to prevent unseating when the engine is hot.

The principal objects of this invention are to maintain the valve guide in accurate alignment with the valve seat, to protect practically the entire length of the valve stem from direct contact with the exhaust gases, to prevent excessive heating of the valve stem, thereby reducing the resultant expansion and permitting a corresponding reduction in the required clearances with the tappets, and to provide a cooling jacket for the valve guide to a point in close proximity to the valve seat.

Further objects and advantages of the invention will become apparent as the disclosure proceeds and the description is read in

connection with the accompanying drawings, in which

Fig. 1 is a diagrammatic side elevation of an internal combustion engine and its appurtenances, organized in accordance with this invention;

Fig. 2 is a partial plan view of the engine with the cylinder head removed;

Fig. 3 is a transverse section through a portion of the engine under the axis of an exhaust valve; and

Fig. 4 is a sectional view of a fragment taken along the line 4—4 of Fig. 2.

In the diagrammatic view of Fig. 1 the engine is indicated generally by A, the radiator by B, the circulating pump by C, its intake connection from the bottom of the radiator by D, its output connection to the cooling jackets by E, and the connection to the radiator by F.

For convenience of illustration the cylinder block 10 is shown as a one-piece casting equipped with a plurality of cylinders 11, each of which is in communication with an intake port 12 and exhaust port 13, each of the latter being controlled by a poppet valve having a stem 14 and a head 15, the latter cooperating with a valve seat 16.

In Fig. 3 the exhaust port 13 has been shown as curving downwardly and outwardly from the seat 16 in substantially the same manner as corresponding ports now in common use. The cylinder walls are provided with a cooling jacket 17, following in general respects the conventional form and serving to permit the circulation of a cooling fluid about the cylinder walls. The head 18 is also equipped with a somewhat conventional jacket 19, in communication with the cylinder jacket 17 through passages 20, arranged adjacent to the exhaust valves and there only.

The stem 14 of the poppet valve is mounted to reciprocate in a valve guide 21, rising from the bottom wall 22 of the jacket 17, and extending through the inner curved wall 23 of the port 13. It is distinguished from valve guides as commonly constructed by projecting upwardly into the port to a point in close proximity to the valve seat 16. On the inner side of the valve guide adjacent to its upper

end the wall 23 is deflected inwardly, as best illustrated in Figs. 2 and 3, to form a pocket 24 extending well up toward the top of the valve guide and in communication with the 5 jacket 17. The upper wall 25 of the pocket is shown substantially horizontal and joining the upright wall 26 of the pocket at substantially a right angle. These walls are joined at each side by lateral walls 27 (Fig. 2), which 10 extend downwardly and inwardly from the corner of the pocket and join with the curved wall 23.

On the outer side of the valve guide 21 the lower portion 28 of the jacket 17, and the 15 upper portion 29 thereof, is connected by an auxiliary jacket 30, which extends along the valve guide across the port 13. The inner wall 31 of this auxiliary jacket is the outer wall of the valve guide and extends upwardly 20 to a point corresponding with the wall 25, where it turns outwardly, as indicated at 32, and then upwardly, blending with the wall of the jacket 17 at 33. The remaining walls of this jacket are somewhat horse-shoe shaped 25 in transverse cross-section and serve to make a passage for cooling fluid to be circulated upwardly along the valve guide and into the upper portion of the jacket 17. The metal forming the walls 25 and 32 becomes 30 a diaphragm or partition extending across the port 13 adjacent to the seat 16, and this wall, together with the auxiliary jacket and the guide, divide the exhaust port into two branches.

35 The cooling water or the liquid delivered by the pump C is communicated, through a header 34 (Fig. 2), to the pipes 35, 36, extending along the jacket 17 adjacent to the ports and forming the manifolds for distributing the water. The pipe 35 is provided with 40 openings or ports 37 below and directed toward pocket 24, whereby the water from the pump is delivered first into the pocket by a jet action, causing rapid circulation of the 45 water and consequent rapid cooling of the walls of the pocket. The pipe 36 is provided with openings or ports 38 below and directed toward the auxiliary jackets 30, whereby cool water directed from the pump 50 is delivered first into the auxiliary jackets and circulated rapidly along the walls thereof to produce corresponding rapid cooling at the outer side of the valve guide.

55 The pipes 36 and 37 distribute all the water delivered by the pump, and, in the preferred construction, release it only at the exhaust valve guides, thus producing the best possible condition for properly cooling of those guides. The passages 20 from the cylinder 60 jacket to the head jacket should be arranged close to the valve guides, and should have a combined capacity no greater than the capacity of the pump to insure the best circulation in the vicinity of the valve guides.

65 The valve guide extends so high that an

inconsiderable portion of the valve stem is exposed to the exhaust gases, practically its entire length being shielded and protected by the valve guide, which in turn is cooled and protected by the jacketed surfaces which extend approximately to the valve seat. In addition to protecting the valve stem from both the direct and indirect action of the hot gases, this construction rigidly braces the upper end of the valve guide and prevents 70 expansion from throwing the valve out of alignment with the axis of the seat, as is commonly the case with the ordinary structure. The efficient cooling of the valve guide and the extension of that guide so far toward the 75 head of the valve, permits the temperature of the stem to be maintained at such a low degree that the required clearance with the tappets can be materially reduced without danger of impairing the seating when the 80 motor is well warmed up.

In the ordinary construction, where the exhaust gases impinge directly against the valve stem for a considerable length below the head, that portion of the valve stem is the 85 hottest part of the entire engine. Heat from it is radiated along the stem in both directions. That which goes to the head raises the temperature of the head and lowers the 90 degree of compression that can be used without having preignition, and increases burning distortion, pitting and wearing of the 95 valves, and the liability of detonation with lean mixtures.

With the present invention this highly 100 heated area, or the high localization of heat on the stem, is eliminated. Instead of conducting heat to the head the stem conducts heat away from the head, maintaining it at a lower temperature and reducing or eliminating the objectionable effects named above 105 and, to a corresponding extent, increasing the efficiency of the engine. In addition there is less elongation of the stem and the tappet clearance can be reduced.

When used in connection with special heat dissipating valves (such as the salt-cooled valves described and claimed by S. D. Heron in application No. 644,480, filed June 19, 1923), the high rate of conductivity of the 115 valve combines with the cooling action of the engine structure here shown to so reduce the working temperature of the valve head that it assists in cooling the valve.

The improved jacket and valve guide is illustrated only in connection with an exhaust valve, and it is here that the invention will find its greatest utility; but there are instances where it may be advantageously applied to the intake valves.

I claim as my invention—

1. In an internal combustion engine, a cylinder, a cooling jacket for the cylinder, a cylinder head, a cooling jacket for the cylinder head, a port communicating with

the cylinder, a poppet valve controlling the port, a seat for the poppet valve, a valve guide extending through the cylinder jacket into the port and terminating in close proximity to the valve seat, an auxiliary cooling jacket in communication with the cylinder jacket and extending along the valve guide across the port, and means for causing a cooling fluid to circulate first through the auxiliary jacket, the cylinder jacket and then through the cylinder head jacket.

2. In an internal combustion engine, a cylinder, a cooling jacket for the cylinder, a port communicating with the cylinder and including curved walls extending through the cylinder jacket, a poppet valve for controlling the port, a seat for the valve, a valve guide extending through the cylinder jacket and projecting into the port to a point in close proximity to the valve seat, a cylinder jacket having a pocket extending along the valve guide through the inner curved wall of the port, means for causing a cooling fluid to circulate through said pocket, an auxiliary jacket extending along the valve guide across the port and connected at its ends with the cylinder jacket, and means for causing a cooling fluid to circulate through said auxiliary jacket.

3. In an internal combustion engine, an upright cylinder, a cooling jacket for the cylinder having substantially top and bottom walls extending laterally from the cylinder and a side wall spaced from the cylinder, a port communicating with the cylinder and curving from the top wall to the side wall of the cylinder jacket, a poppet valve for the port, a seat for the poppet valve on the top wall of the jacket, a valve guide extending from the bottom wall of the cylinder jacket through the inner curved wall of the port and to a point in close proximity to the valve seat, the top wall having a portion extending across the port and connected with the upper end of the valve guide, and an auxiliary cooling jacket extending along the valve guide across the port and communicating at its ends with the cylinder jacket.

4. In an internal combustion engine, an upright cylinder, a cooling jacket for the cylinder having substantially top and bottom walls extending laterally from the cylinder and a side wall spaced from the cylinder, a port communicating with the cylinder and curving from the top wall to the side wall of the cylinder jacket, a poppet valve for the port, a seat for the poppet valve on the top wall of the jacket, a valve guide extending from the bottom wall of the cylinder jacket through the inner curved wall of the port and to a point in close proximity to the valve seat, the top wall having a portion extending across the port and connected with the upper end of the valve guide,

a pocket in the cylinder jacket extending along the inner side of the valve guide to a point in close proximity with the valve seat, means for projecting a jet of cooling fluid into the pocket, an auxiliary cooling jacket extending along the valve guide across the port and connected at its ends with the cylinder jacket, and means for projecting a jet of cooling fluid through said auxiliary jacket.

5. In an internal combustion engine, an upright cylinder, a downwardly and outwardly curved port communicating with the cylinder, a poppet valve controlling said port, a valve seat at the upper end of the port for said valve, a valve guide extending along the valve into the port in close proximity to the valve seat, a cooling jacket for the cylinder extending around the lower portion of the valve guide and around the port, and an auxiliary jacket extending along the valve guide through the port and connected at its ends with the cylinder jacket.

6. In an internal combustion engine, a cylinder, a cooling jacket for the cylinder, a port for the cylinder divided into two branches separated by portions of the cooling jacket, a poppet valve controlling the port, and a valve guide between the branches of the port and protected by the cooling jacket.

In testimony whereof I affix my signature.

ROBERT JARDINE.
